UNITED STATES PATENT OFFICE.

WILLIAM DAVIS, OF FITCHBURG, MASSACHUSETTS.

DESIGN FOR A MIRROR-FRAME.

SPECIFICATION forming part of Design No. 24,278, dated May 7, 1895.

Application filed February 18, 1895. Serial No. 538,899. Term of patent 7 years.

To all whom it may concern:

Be it known that I, WILLIAM DAVIS, of Fitchburg, in the county of Worcester and State of Massachusetts, have invented and 5 produced a new and original Design for Frames for Mirrors, Pictures, and the Like, of which the following is a specification, reference being had to the accompanying drawing and to the letters of reference marked 10 thereon.

The characteristic feature of my present invention consists as will be seen from the drawing, of an outer border or frame having at the center of the side pieces a convex molding A on each side of which are the truncated cone shaped moldings A'. From these last moldings extend the rounded moldings A² tapering from the middle portion toward each end, having on the faces a vine like ornamentation f. Beyond the portion A² there is 15 a series of hollow moldings F', and after them a series of the truncated cone like moldings, which are followed by the convex molding and truncated cones, similar to that at the 20 middle of the side. At each end of the top and bottom of the frame there is repeated the convex molding with the truncated cones, as

at the sides, and at the center, between the moldings last mentioned there are repeated the rounded tapering moldings with their 30 vine ornamentations similar to those on the sections lettered A². Ornamental blocks E are located at the corners where the side, top and bottom pieces of the frame meet, and upon these blocks are crossed vine ornamentations 35 e. Within the outer frame or border there is a field B presenting a roughened or corrugated appearance and at the inner margin of this field there is a vine-like bordering C, composed of a vine or stalk with leaves and fruit, 40 as shown. At the corners of the bordering there are angle pieces C' with which the bordering joins to present a finished appearance.

The interior space in the frame is divided by a rail D across which runs a vine-like molding 45 similar in appearance to the molding C.

Having thus described my invention, what I claim as new is—

The design for a mirror frame and the like substantially as herein shown and described. 50

WILLIAM DAVIS.
